UNITED STATES PATENT OFFICE.

EDGAR CLARENCE WILEY, OF INDEPENDENCE, VIRGINIA.

AUTOMATIC GRAIN-WEIGHER.

SPECIFICATION forming part of Letters Patent No. 377,417, dated February 7, 1888.

Application filed October 21, 1887. Serial No. 252,996. (No model.)

To all whom it may concern:

Be it known that I, EDGAR CLARENCE WILEY, a citizen of the United States, residing at Independence, in the county of Grayson and State of Virginia, have invented a new and useful Improvement in Automatic Grain-Weighers, of which the following is a specification.

My invention relates to an improvement in automatic grain-weighing machines; and it consists in the peculiar construction and combination of devices, that will be more fully set forth hereinafter, and particularly pointed out in the claims.

15 In the drawings, Figure 1 is a side elevation of a grain-weighing machine embodying my improvements. Fig. 2 is a vertical sectional view of the same. Fig. 3 is a top plan view. Fig. 4 is a horizontal section taken on 20 the line *x-x* of Fig. 1.

A represents a tripod comprising the legs B and C and the cap D, attached to the upper ends of the legs. On the said cap is secured a cross-bar, E, provided at its extremities with 25 vertical openings F. In the center of the cap is a vertical opening, G.

H represents a curved arm which connects the two legs B and extends inwardly to a point in line with the center of the cap D, and 30 is provided with a vertical opening, I.

K represents a vertically movable shaft which has its lower end journaled in the opening I, and is journaled near its upper end in the opening G. Fitted on the upper end of the said shaft K is a collar, L, which bears upon the upper side of the cap D, and in which the shaft K is free to rotate. To the upper side of this collar is attached the central portion of a circular platform, M, which 35 40 platform is provided on one side with a V-shaped opening, N, of suitable dimensions. From opposite sides of the platform M depend guide-arms O, the lower ends of which pass through the openings F in the ends of the cross-bar E.

45 From the foregoing description it will be understood that the platform M is free to move vertically with the shaft K, but that it is prevented from rotating with the said shaft by the arms O and the cross-bar E.

P represents a measuring-head which is provided with a central hub, R, rigidly secured

to the upper end of shaft K, vertical partition-boards S, which radiate from the said hub, and a circular vertical board, T, which connects the outer ends of the boards S and forms the outer sides of the measuring-compartments U, which are formed between the boards S. Each of these compartments U corresponds in size and shape with the opening 60 N in the platform.

V represents a vertical cylindrical sleeve which is fitted loosely on the lower portion of the shaft K and bears upon the upper side of the curved arm H. Rigidly secured to the 65 said sleeve or formed integrally therewith, as may be preferred, is a horizontal gear-wheel, W, provided with bevel gear-teeth. On the upper end of the sleeve V is formed a series of ratchet or clutch teeth, X.

70 Y represents a spring-arm which has its outer end attached to one of the tripod-legs, B, and has its lower end bearing on the upper side of the wheel W, near the center thereof, so as to prevent the said wheel and the sleeve V from rising on the shaft.

Z represents a horizontal circular disk which is rigidly attached to the shaft K at a suitable distance from the lower end thereof, the said disk being arranged above the upper end of the 80 sleeve V. On the lower side of the said disk, at diametrically-opposite points, are formed depending studs A', which are adapted to engage the teeth X of the sleeve when the shaft is lowered, as will be hereinafter explained. 85 Recesses B' are formed in the outer edge of the disk Z at diametrically-opposite points, there being as many of these recesses as there are compartments in the head P, and the said recesses corresponding with the boards S in their 90 relation to the shaft K.

C' represents a horizontal arm which projects inward from one of the tripod-legs, B, and is provided on its inner end with a roller, D'.

E' represents a horizontal arm which extends outward from the tripod-leg C and is provided with suitable bearing-brackets, F', in which is journaled the horizontal driving-shaft G'. The said shaft may be actuated by any suitable motor, or it may be rotated by 100 means of a crank, H', as shown. To the inner end of this shaft is rigidly attached a bevel-pinion, I', which meshes with the wheel W.

K' represents a scale-beam which is ful-

crumed at a suitable distance from its inner end between a pair of depending arms, L', at the upper end of the tripod or supporting frame. On the said scale-beam is a movable weight, M'.

N' represents a lever which is fulcrumed to the tripod-leg C, near the lower end thereof, and extends under the shaft K, and is provided with an opening in which the lower end of the said shaft is stepped. The free end of this lever N' is connected to the inner end of the scale-beam by means of a rod, O', and a link, P', as shown.

R' represents a depending handle which is connected to the scale-beam, and by means of which the outer end of the latter may be lowered by hand when it is desirable to do so.

The operation of my invention is as follows: The scale-beam, by drawing upward on the rod 20 O', causes the free end of the lever N' to be normally elevated, and the said lever moves the shaft K upward, and consequently elevates the platform M and the measuring-head T. The weight is adjusted on the scale-beam to 25 the number of pounds which constitute the unit of measure or weight. When the invention is adapted to be used in connection with thrashing-machines, an endless elevator (not shown) is employed to discharge the grain as 30 it comes from the thrasher into the compartment U of the measuring-head which is next adjacent to the opening N. When the said compartment has received the required weight of grain, the weight of the platform and of 35 the measuring-head counterbalances the leverage of the scale-beam, and the said platform and measuring-head are thereby caused to descend, and consequently lower the shaft K and the lever N' and raise the scale-beam K'. 40 When the platform is in its normal elevated position, the disk Z is elevated, so that the roller D' engages one of its openings B', and consequently prevents the shaft from rotating; but when the said shaft is lowered by the descent of the platform and measuring-head, as 45 before described, the disk K is also lowered, thereby causing the roller D' to clear the upper side of the said disk, and causing the studs A' to engage the notches or teeth at the upper 50 end of the sleeve. The rotation of the shaft G', which, it will be understood, is normally in constant motion, will be thereby instantly communicated to the shaft K through the gear-wheels W and I', and consequently the measuring-head will be caused to rotate through a 55 portion of a circle on the upper side of the platform M, and thereby discharge the contents of its loaded compartment through the opening N into a suitable spout or trough, 60 which delivers the grain into a bag or other suitable receptacle. As the filled compartment moves over the opening N, and thereby becomes discharged of its contents, the next adjacent compartment moves under the discharge end of the elevator in position to be 65 filled.

As soon as the grain is discharged from the

measuring-head, the latter and the platform become lightened to such an extent that the leverage of the scale-beam overcomes their 70 gravity, and consequently the shaft O is immediately elevated to its former initial position, thereby raising the platform and measuring-head and causing the roller D' to become engaged with the next adjacent opening 75 B' in the disk Z. As the said disk rises, it becomes disconnected from the sleeve G, as will be very readily understood, and thereby leaves the wheel W free to rotate with the shaft G' without turning the shaft K.

8c A suitable registering device may be connected to the shaft K in order to keep a register of the quantity of grain weighed.

In order to adapt the machine for measuring grain accurately, I adjust the weight on the 85 scale-beam so as to cause the measuring compartment of the head into which the grain is being poured to become more than level full before the scale-beam is overbalanced and the platform and measuring-head descend. I also 90 secure to the platform a support, a, to which is attached an arm, b, that extends inwardly in a horizontal direction over the measuring-head, and just above the latter. By this device when the platform descends and rotation 95 is imparted to the head the arm b strikes off the excess or surplus grain above the level of the upper side of its measuring-head and sweeps the surplus or excess grain into the next compartment, as will be very readily understood.

Having thus described my invention, I claim—

1. The combination of the tripod or frame having the cap D, the arms L', depending from 105 said cap, and scale-beam fulcrumed to the said arms, the link P' at the inner end of the scale-beam, the lever N', fulcrumed to one of the tripod-legs, the rod O', connecting the free end of said lever to the link P', the vertically-movable platform on the upper side of the cap and having the discharge-opening, the vertically-movable shaft K, journaled in the cap 110 and platform and supported by the lever N', the revoluble head secured to the upper end 115 of said shaft and resting on the platform, said head having the compartments, and the gearing to rotate the shaft when the same is lowered, substantially as described.

2. The combination of the vertically-movable shaft having the clutch, the rotating wheel 120 W, journaled loosely on the said shaft and having the sleeve adapted to be engaged by the clutch when the shaft is lowered, for the purpose set forth, the platform movable vertically with the shaft and provided with the opening N, means to prevent the said platform from rotating, the measuring-head secured to the upper end of the shaft, revoluble therewith, arranged on the platform, and having the compartments U, the scale-beam having 125 the adjustable weight, and connections between the said scale-beam and the shaft, substantially as described.

3. The combination, in an automatic grain-weighing machine, of the vertically-movable platform having the opening N, the vertically-movable shaft extending through the said platform and having the measuring-head secured thereto, the said head being provided with the compartments U, the rotating wheel W, journaled loosely on the shaft, the stop-disk Z, rigidly secured to the shaft and adapted to engage the wheel W when the shaft is lowered, the scale-beam, connections between the same and the shaft to normally elevate the latter, and a detent-roller adapted to engage the disk when the shaft is raised, for the purpose set forth, substantially as described.

4. The combination of the vertically-movable shaft, the vertically-movable platform supported thereby and having the opening N, the measuring-head on the upper side of the platform, having the compartments U and revolvable with the shaft, the rotating wheel W, journaled loosely on the shaft, the clutch adapted

to connect the shaft to the said wheel when the shaft is lowered, the lever N', supporting the shaft, and the scale-beam connected to the said lever and adapted to normally elevate the same and the platform and measuring-head, substantially as described.

5. The combination of the supporting-frame, the vertically-movable counterbalanced shaft journaled therein, the platform having the discharge-opening supported on the said shaft and having the guide-arms whereby it is prevented from rotating, and the measuring-head attached to the shaft, revoluble therewith, and having the compartments U, substantially as described.

In testimony that I claim the foregoing as my own I have hereto affixed my signature in presence of two witnesses.

EDGAR CLARENCE WILEY.
